UNITED STATES PATENT OFFICE.

JAMES A. WILSON, OF CENTRAL FALLS, RHODE ISLAND.

COMBINED REED AND HEDDLE-FRAME.

1,309,674.

Specification of Letters Patent. Patented July 15, 1919.

Application filed April 4, 1919. Serial No. 287,386.

To all whom it may concern:

Be it known that I, JAMES A. WILSON, a citizen of the United States, residing at Central Falls, in the county of Providence, State of Rhode Island, have invented certain new and useful Improvements in Combined Reeds and Heddle-Frames, of which the following is a specification.

My invention relates to a combined reed and heddle-frame and consists of improvements in the construction and arrangement of the heddles or dents in the frame. A particular object of my improvement is to provide a heddle-frame for hand-loom 10 which may be employed both as a harness for shifting the warp-yarns, and as a reed for beating the weft-threads into place.

The improvement is fully described in the following specification, illustrated by the accompanying drawings, in which like reference characters designate like parts. In the drawings:

Figure 1 is a perspective view of my improved heddle-frame and reed;

Fig. 2, a cross-sectional view of the same;

Fig. 3, a detail view showing the method of holding the heddles or dents in spaced relation in the frame;

Fig. 4, a perspective view of a modified form of the heddle or dent; and

Fig. 5, a plan view of the blank from which this form of heddle is constructed.

Referring first to Fig. 1 my improved heddle-frame and reed F comprises, in general, upper and lower longitudinal frame-members 2 and 3, between which are supported the vertical heddles or dents 4 arranged in spaced relation therewith. The frame-members 2 and 3 are preferably constructed in the form of tubular rods having openings 5 and 6 extending along their lower and upper sides, respectively, to adapt them to inclose the opposite ends of the heddles 4. The ends of the two frame-members 40 or rods 2 and 3 are braced apart by uprights 7, 7 consisting of flat bars extending therebetween. The bars 7 have their ends inserted in the openings 5 and 6 of the rods 2 and 3 and are soldered, brazed or otherwise secured in place therein. The ends of the rods 2 and 3 are then closed by circular caps 8 soldered thereto or the end openings 45 may be filled with solder to provide a smooth finish.

The heddles or dents 4 consist of relatively thin, flat bars of a width to adapt their ends to fit snugly into the openings 5 and 6 in the rods 2 and 3. When arranged in this manner extending between the two rods the heddles 4 are maintained in spaced relation by coiled, wire springs 9 and 10, see Figs. 2 and 3. Referring particularly to Fig. 3, one coil of the spring 10 separates each two heddles and the remaining space in the hollow of the rod 3 is filled with solder to hold the 65 parts in permanent fixed relation.

To adapt my improved reed and heddle-frame to be used as a harness I provide the heddles 4 with guide-eyes for the warp-yarns to restrict the movement of the latter up and down in the spaces between the heddles. In the preferred embodiment of the invention shown in Fig. 1 each alternate pair of heddles 4, 4 is connected by two blocks 11, 11, spaced a slight distance apart at the center of the heddles. These blocks 11 may be formed of solder poured in a molten state between the heddle-bars and confined in place by molds formed of plaster or other material which is afterward removed. 80 After the solder has hardened the blocks 11 are filed down and rounded off on their edges to provide smooth surfaces which will not abrade the yarns. If desired, the blocks 11 might be formed of metal soldered or 85 brazed to the sides of the heddles, but I have found that they may be constructed more cheaply by pouring solder in to fill the spaces.

In Figs. 4 and 5 I have illustrated a modified form of the heddles in which the cross-ties or connecting pieces are constructed as integral parts of the heddle-bars. In this embodiment of the invention a pair of integral heddles 12, 12 are stamped or punched 90 out of sheet-metal with their opposite edges connected by cross-strips or tabs 13, 13. Fig. 5 illustrates the heddle-blank made in this form and by bending the two bars 12, 12 into position with their flat sides parallel, as shown in Fig. 4, the tabs 13 are caused to form connecting cross-strips extending between the heddles. This form of heddle is assembled in the frame in the same manner as the solder-connected bars or dents 4 above 100 described and the arrangement of the thread-eyes between the heddles will be substantially the same, as illustrated in Fig. 4.

In applying my improved reed and heddle-frame to use in the loom the warp yarns y , see Fig. 1, are drawn through the spaces between the heddles 4 with each alternate yarn 5 y' threaded through the central eye or opening 15 formed by the two spaced blocks 11, 11. This provides that when the heddle-frame F is used as a harness one set of yarns y' may be raised above or depressed below 10 the other set y to form a shed through which the shuttle is passed. The opening of the shed is effected by simply moving the frame F up and down to cause the yarns y' confined in the guide-eyes 15 to move 15 therewith while the other yarns y , being free to slide in the unrestricted spaces between the heddles 4, remain at their normal level. After the shed has been opened in this manner, and the shuttle passed through 20 it, the weft yarn inserted by the shuttle is beaten up into place at the fell of the fabric by carrying the frame F bodily forward. My improved heddle-frame is thus utilizable both as a harness and as a reed, the heddles 25 4 serving to manipulate the warp-yarns to form the shed and also acting as dents to beat the filling or weft-yarns into the fell of the cloth.

In Fig. 1 I have illustrated the thread- 30 eyes 15 for the yarns y' as arranged in alternate succession along the heddles. This arrangement is employed for plain weaving, but for fancy weaves the eyes may be disposed in different relation in accordance 35 with the design or pattern to be produced in the cloth. For instance, the thread-eyes could be grouped together in pairs, alternating with pairs of heddles without eyes, or any other suitable grouping of the yarns 40 could be provided for.

The drawings show the heddle-bars as somewhat thicker than what are generally used, and the width of the spaces between the bars is also exaggerated in order to 45 show the structure of the parts more clearly. In practice the heddles employed are extremely thin and are placed close together so that a relatively large number may be used in the frame for weaving fine yarns. 50 My improved method of joining the opposite sides of the heddles by blocks of solder, to form the guide-eyes for the yarns, is of particular advantage as providing for this close-spacing of the heddles in the frame F. 55 Heretofore it has been the general practice to employ heddles of twisted wire in the loom-harness the two wires being bowed apart at points to form the guide-eyes. In other cases the flat bars from which the 60 heddles are constructed are punched with holes which serve as guide-eyes, but with such an arrangement it is difficult to thread the yarns through the eyes. With this latter form of heddle the yarn must make a 65 sharp bend in passing through the guide-

eye when the heddles are placed in alignment with their sides parallel, so that the yarn takes up more space and is also liable to be chafed and abraded. Neither of these previously used forms of heddles is adapted 70 for use in a frame serving both as harness and reed because they cannot be spaced closely enough to provide for using the heddles as dents for beating up the filling. With my present improved arrangement the 75 heddles may be spaced almost in contact, leaving only enough space for a fine yarn to pass between them, while at the same time the connecting blocks between the heddles provide for controlling the yarns as 80 in a harness, but without requiring that they be threaded through openings or eyes in the heddles.

Various modifications other than that herein shown might be made in the structure and arrangement of the parts of my improved heddle-frame and reed without departing from the spirit or scope of the invention, therefore without limiting myself to the exact embodiment described and illustrated, what I claim is:

1. In a combined reed and heddle-frame, the combination with opposite parallel frame-members, of a series of heddles consisting of relatively thin flat bars extending 95 between the frame-members in parallel spaced relation therealong, and spaced blocks connecting the opposite sides of adjacent heddles of certain pairs, said blocks forming restricted openings adapted to 100 serve as guide-eyes for the yarns passing between the heddles.

2. In a combined reed and heddle-frame, the combination with the opposite parallel frame-members, of a series of relatively thin flat heddle-bars supported at their ends on the frame-members and arranged in parallel spaced relation therealong, and means connecting the opposite sides of adjacent heddles of certain pairs at points spaced 105 apart to provide restricted openings adapted to serve as guide-eyes to control the vertical movement of the yarns passing between the heddles.

3. In a combined reed and heddle-frame, 115 the combination with upper and lower parallel frame-members formed of hollow rods having openings on their bottom and top sides respectively, of a plurality of heddles formed of relatively thin flat bars arranged 120 with their ends secured in the openings in the frame-members, and blocks of solder connecting the sides of adjacent heddles of certain pairs and arranged in spaced relation to form guide-eyes for the yarns passing 125 between the heddles.

4. In a combined reed and heddle-frame, the combination with top and bottom frame-members formed of tubular rods having openings on their bottom and top sides re- 130

spectively, of a plurality of flat sheet-metal heddles arranged with their ends inserted in the openings of the rods in spaced relation therealong, coiled wire springs extending within the sides of the rods with a coil of the wire separating each two heddles, and cross-pieces extending between the sides of adjacent heddles of certain pairs in spaced relation thereon to provide restricted openings adapted to serve as guide-eyes for 10 the yarns passing between the heddles.

In testimony whereof I affix my signature.

JAMES A. WILSON.
